UNITED STATES PATENT OFFICE.

CHARLES BOOZ, OF BUFFALO, NEW YORK, ASSIGNOR, BY MESNE ASSIGNMENTS, TO GEORGE K. BIRGE, OF SAME PLACE.

DESIGN FOR WALL-PAPER.

SPECIFICATION forming part of Design No. 24,823, dated October 29, 1895.

Application filed September 27, 1895. Serial No. 563,987. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of an arrangement of broad interlacing lines or stripes forming square open panels with leafy scroll-like ornaments interlacing with said stripes or lines, as represented in the accompanying drawing. 15 The border of said design is formed of broad interlacing lines or stripes forming pointed oval panels, through which runs a straight

line or stripe with leafy scroll-like ornaments interlacing with said stripes or lines, as shown. An ornamental band formed of a horizontal 20 stripe with leafy scroll-like ornaments wound around said band forms the bottom of said border, as shown in the drawing.

What I claim is—

1. The design for wall paper herein shown 25 and described.
2. In the design for wall paper the border herein shown and described.

Witness my hand this 24th day of September, 1895.

CHARLES BOOZ.
